UNITED STATES PATENT OFFICE

164,173

TELEPHONE BRACKET FOR MEMORANDUM PAD

Burton H. Ives, Chicago, Ill.

Application October 21, 1950, Serial No. 12,653

Term of patent 14 years

(Cl. D28—14)

To all whom it may concern:

Be it known that I, Burton H. Ives, a citizen of the United States, residing in the city of Chicago, county of Cook, and State of Illinois, have invented a new, original, and ornamental Design for a Telephone Bracket for Memorandum Pad, of which the following is the specification, reference being made to the accompanying drawing, forming a part hereof.

Fig. 1 is a perspective view of a telephone bracket for memorandum pad showing the manner in which it is attached to the French-type telephone;

Fig. 2 is a front elevational view of the same, partly in cross section; and

Fig. 3 is a side elevational view of the same. The portions of the drawings shown in dotted lines are included as illustrative of the applied use of the device.

I claim:

The ornamental design for a telephone bracket for memorandum pad, as shown and described.

BURTON H. IVES.
